FLUID PRESSURE CONTROL MECHANISM

Wilfred A. Eaton, Elyria, Ohio, assignor to Bendo-Westinghouse Automotive Air Brake Company, Elyria, Ohio, a corporation of Delaware

Application October 5, 1943, Serial No. 505,067

12 Claims. (Cl. 121—38)

This invention relates to fluid pressure control mechanism, and more particularly to mechanism of the above type for controlling the operation of the throttle of a vehicle engine.

It has previously been proposed to employ mechanism of this type for controlling the throttle of a vehicle engine, the throttle being actuated by means of a cylinder provided with a piston slidably mounted therein, but difficulties have been experienced in obtaining a smooth and accurate control of the throttle valve due to the inherent friction between the packing of the piston and the cylinder walls, and it is accordingly an object of the present invention to provide throttle control mechanism so constituted as to overcome these difficulties.

It has also been proposed to employ substantially frictionless flexible pressure responsive members or diaphragms for actuating the vehicle engine throttle, but difficulty has been experienced in systems of this type due to the short life of the diaphragm when operated at strokes sufficient to provide operation of the throttle over the entire operating range, and it is therefore a further object of the invention to provide throttle control mechanism so constituted as to overcome the above difficulties and combine the advantages of operation by means of diaphragms as well as cylinders and pistons.

Yet another object of the invention is to provide, in connection with a system of the above type, means for minimizing the effects of friction between the piston and cylinder wall in order to obtain a smooth and accurate control of the throttle over the entire range of operation.

The above and other objects and novel features of the invention will appear more fully herein-after from the following detailed description when taken in connection with the accompanying drawing. It is to be expressly understood, however, that the drawing is for purposes of illustration only and is not designed as a definition of the limits of the invention, reference being had for this purpose to the appended claims.

In the drawing, wherein the single figure illustrates diagrammatically, and partially in section, a throttle controlling mechanism constructed in accordance with the principles of the present invention, an engine 4 is provided with a throttle valve 5 operated by means of a throttle lever 6 suitably attached thereto. A throttle rod 7 is slidably mounted in brackets 8 and 9 carried by the vehicle structure and the engine respectively, the left end of the rod being connected with the throttle lever by means of a link 10, pivotally

connected with both the lever and rod. The throttle valve is shown in closed or idling position, and is normally maintained in this position by means of a spring 11 interposed between the bracket 9 and a collar 12 carried by the throttle rod, the spring serving to normally maintain the rod in abutment at its right end with a suitable stop 13 mounted on the structure of the vehicle.

A fluid motor 14 is provided for operating the throttle, this motor including a cylinder 15 provided with a bore 16, together with a piston 17 slidably mounted therein and provided with a piston rod 18. In order to prevent leakage of fluid pressure past the piston, the latter is also

15 provided with a packing cup 19, which may be of leather or any other suitable material, and which is in frictional engagement with the wall of the cylinder. The portion of the cylinder at the left side of the piston is connected with atmosphere by means of a port 20, and fluid pressure is supplied to the right end of the cylinder by means of an operator's control valve 21, which may be constructed in accordance with the principles set forth in the patent to William J. Andres and Roy

25 S. Sanford, No. 2,133,275, dated October 18, 1938. This control valve is provided with a casing 22 having an operating pedal 23 pivotally mounted thereon by means of a suitable pin 24. In addition to the foregoing, the casing is provided with

30 an inlet connection 25, an outlet connection 26 and an exhaust connection 27, and it will be understood on reference to the above named patent, that with the operating pedal in the position shown, the valve serves to prevent communication between connections 25 and 26 and to permit communication between connections 26 and 27, while on depression of the pedal by the operator, the valve serves to dis-establish communication between connections 26 and 27 and to permit communication between connections 25 and

35 26, in order to establish an output pressure at the connection 26 which is substantially proportional to the degree of depression of the control pedal. The inlet connection is connected to a suitable fluid pressure supply reservoir 28 through the medium of a conduit 29, the reservoir being supplied with fluid pressure from a suitable compressor or pump, not shown, by means of a conduit 30, it being understood that while the system is designed primarily for operation by compressed air, hydraulic operation may be utilized with equal effectiveness without departing from the spirit of the invention. The outlet connection 26 is connected with the cylinder by means of

40 45 50 55 conduits 31 and 32 as shown. In addition to the

fluid motor for actuating the throttle valve, a fluid actuator 33 is provided comprising casing members 34 and 35, as well as a flexible pressure responsive member or diaphragm 36 clamped between the two casing members as shown, in order to define an atmospheric chamber 37, connected with atmosphere by means of a port 38, and a chamber 39 which is connected with the conduit 32 and therefore with the outlet connection 26 of the control valve.

Novel means are provided for establishing operating connections between the piston and the throttle rod as well as between the diaphragm and the throttle rod, such means including an equalizing lever or beam 40 pivotally mounted on the throttle rod by means of a pivot pin 41, the lower end of the beam carrying a pivot pin 42 and the upper end of the beam being provided with a pivot pin 43. The left end of this piston rod is provided with a clevis 44 having an elongated slot 45 in engagement with the pin 42 in order to compensate for angularity between the lever 40 and the piston rod 18 during operation of the device, the upper end of the lever having pin 43 connected with the diaphragm 36 by means of a clevis 46 having an elongated slot 47 in engagement with the pin, the clevis being connected with the diaphragm by means of a rod 48 and a pin 49 as shown.

As shown in the drawing, the fluid motor 14 and the fluid actuator are suitably bolted to a bracket 50 formed on the cylinder. For purposes of this description, it is considered that the fluid motor is initially so assembled with respect to the lever 40 and the fluid actuator 33 as to cause the diaphragm 36 to remain in neutral position. Movement of the diaphragm to the right or left is limited respectively by means of a stop 51 formed on the casing member 35 and a collar 52 formed on the right end of the rod 48, the latter contacting a boss 53 on the casing member 34 when the diaphragm is moved to the left a predetermined amount.

In the embodiment shown in the drawing, the areas of the piston and diaphragm are designed to be substantially equal and in like manner the lever 40 is so connected to the throttle rod 7, the piston rod 18 and the actuator rod 48 as to divide the lever into substantially equal lever arms 54 and 55, it thus being apparent that in the event equal pressures are supplied to both the cylinder and the actuator, and assuming that there is no friction between the piston and the cylinder wall, the moments exerted on the lever 40 with respect to the pivot point 41 will be equal and there will be no tendency for the lever to rotate about the pivot 41. Although the parts are illustrated as being proportioned in this manner for purposes of convenience of description, it will be further understood that in the event it is desired to make the area of the piston larger than that of the diaphragm, for example, the pivot point 41 will be changed in such a manner that the length of the lever arm 55 is increased with respect to that of the lever arm 54 in such a manner that the opposing moments about the pivot point bear the same relation as that above described, the relative dimensions of the areas of the piston and diaphragm thus being a matter of convenience, provided that the relationship of the parts is so maintained that the force exerted separately by either the piston or the diaphragm, neglecting friction, is substantially the same at the point 41 when the same pressure is acting on the diaphragm and on the piston.

In operating the device, depression of pedal 23 will serve to operate the control valve to supply a desired increment of pressure to the cylinder and to the chamber 39, and in the event of appreciable friction between the packing cup 19 and the cylinder wall, the lever 40 will pivot momentarily about the pin 42, and the rod 48 will be moved to the left until the collar 52 abuts the boss 53, the throttle rod 7 moving through half the distance moved by the rod 48. In the event the allowable travel of the diaphragm is properly proportioned with respect to the friction between the packing cup and the cylinder, a point will be reached prior to abutment of the collar 52 with the boss 53, such that increasing pressure in the cylinder will be sufficient to overcome the friction of the packing cup, whereupon the piston will also move to the left in order to impart further movement to the throttle rod 7, the lever during this type of operation tending to pivot about the pin 43. When this action occurs, the friction of motion of the packing cup will be less than the static friction, and the force exerted by the piston will thereupon tend to return the diaphragm toward neutral position, it being understood that this type of operation is facilitated by the fact that with diaphragms of the type illustrated, the output of the diaphragm in response to a given pressure tends to decrease as the diaphragm moves further away from its neutral position. Thus when the piston moves to the left, the diaphragm will be returned partway to its neutral position, and on the application of a further increment of pressure to the motor and actuator, the action already described will again take place in order to provide immediate movement of the throttle rod and throttle in response to the increased pressure, regardless of the fact that movement of the piston is momentarily prevented by the inherent friction existing between the packing cup and the cylinder, as well as between the piston itself and the cylinder.

During operation of the control valve to release fluid pressure from the motor and actuator, the force exerted by the piston and diaphragm will be decreased and the spring 11 will therefore tend to return the rod 7 toward stop 13 and to close the throttle. During this type of operation, the friction between the packing cup and the cylinder wall will again tend to prevent immediate operation of the throttle in response to a reduction of pressure in the motor and actuator, but in view of the fact that the movement of the diaphragm is substantially without friction relative to the casing, the lever 40 will again pivot in a clockwise direction about the pin 42, and the diaphragm will move toward the stop 51 until such time as the pressure in the cylinder 15 has decreased sufficiently to permit the spring 11 to overcome the friction of the packing cup, whereupon the piston will be moved to the right. Here again, the friction of motion will be less than the static friction, and the diaphragm will tend to return again toward neutral position in order to condition the actuator for a subsequent throttle controlling operation in response to a change in the pressure supplied to the actuator and cylinder. In addition to the foregoing, it is pointed out that in connection with previous devices wherein the throttle was controlled by a piston slidably mounted in the cylinder, the operation has been very erratic due to the inherent difference between the static friction and the friction of motion of the piston and the cylinder wall, and the diaphragm utilized in the present mech-

anism tends to absorb the shock which occurs when the piston starts to move, and minimizes the erratic action which was formerly experienced with mechanisms of this type. It will be seen from the foregoing that with the parts properly proportioned in accordance with the principles of the present invention, the only difference in the force exerted at the point 41 to move the throttle rod by the diaphragm and the piston will be that force due to friction between the piston and the cylinder wall, it being noted that the diaphragm, which is inherently frictionless and which inherently has a relatively short stroke, serves to insure immediate movement of the throttle in response to variations in pressure in the actuator and motor, while the cylinder and piston, which have inherently high frictional characteristics, serve to provide the necessary stroke for insuring further operation of the throttle over the entire range.

In the event it is desired to so tension or preload the spring 11 as to insure positive abutment of the throttle rod 1 with the stop 13 at all times when the control valve is in released position, it will be understood that the graduating spring of the control valve may be preloaded in order to insure immediate response of the throttle control mechanism, as more fully pointed out in the above referred to patent.

While one embodiment of the invention has been illustrated and described with considerable particularity, it is to be expressly understood that same is not limited thereto but may be embodied in various forms. Various changes in the shapes and sizes of the various parts may likewise be made without departing from the spirit of the invention, as will be readily apparent to those skilled in the art. Reference will, therefore, be had to the appended claims for a definition of the limits of the invention.

What is claimed is:

1. The combination with a device to be actuated, of a fluid motor for actuating the device including a cylinder and a piston slidably mounted therein, a fluid actuator for the device comprising a casing and a flexible pressure responsive member mounted therein adapted for limited movement with respect to the degree of movement of the piston, means including a control valve having a connection with the cylinder and casing for controlling the pressure of fluid therein and for concurrently subjecting the piston and member to the same pressure, and means for connecting said device with the piston and with the pressure responsive member including a beam having a connection at one end with the piston, a connection at the other end with the pressure responsive member, and a connection with the device positioned intermediate the last named connections.

2. The combination with a device to be actuated, of a fluid motor for actuating the device including a cylinder and a piston slidably mounted therein, an operating lever for the device having a connection with the device, a connection with the piston, and a fulcrum, means for moving said fulcrum including an actuator having a casing and a substantially frictionless flexible pressure responsive member mounted therein for limited movement with respect to the movement of the piston and connected with the fulcrum, and means including a control valve having a connection with the motor and actuator for controlling the pressure of fluid in said cylinder and

75 casing and for subjecting said piston and member to the same pressure at all times.

3. The combination with a device to be actuated, of a fluid motor for actuating the device including a cylinder and a piston slidably mounted therein, an actuator for the device having a casing and a flexible pressure responsive member mounted therein for limited movement with respect to the movement of the piston, means including a control valve having a connection with the cylinder and casing for controlling the pressure of fluid therein and for subjecting the piston and member to the same pressures at all times, and means for connecting said piston, pressure responsive member and device including a beam connected with the device having a lever arm connected with the piston and a lever arm connected with the pressure responsive member, the product of the area of the piston and the 10 length of the lever arm connected thereto being substantially equal to the product of the area of the pressure responsive member and the length of the second named lever arm.

4. The combination with a device to be actuated, of a fluid motor for actuating the device including a cylinder and a piston slidably mounted therein, an actuator for the device including a casing and a flexible pressure responsive member mounted therein for limited movement with respect to the movement of the piston, said member having an area substantially equal to that of the piston, means including a control valve having a connection with the cylinder and casing for controlling the pressure of fluid therein and for subjecting the piston and member to the same pressure at all times, and means for connecting said piston, pressure responsive member and device including an equalizer beam having a connection at one end with the piston, a connection 20 at the other end with the pressure responsive member, and a connection with the device positioned substantially midway between the other two connections.

5. The combination with a device to be actuated, of a fluid motor for actuating the device including a cylinder and a piston slidably mounted therein, an actuator for the device including a casing and a flexible pressure responsive member mounted therein for limited movement with respect to the movement of the piston, means including a control valve having a connection with the cylinder and casing for controlling the pressure of fluid therein and for subjecting the piston and member to the same pressure at all times, and means including an equalizer for connecting said piston, pressure responsive member and device, said equalizer being proportioned to permit operation of said device by said piston and pressure responsive member concurrently when the friction between said piston and cylinder is less than a predetermined value and to permit limited operation of the device by the pressure responsive member separately when said friction exceeds said predetermined value.

6. The combination with a device to be actuated, of a fluid motor for actuating the device including a cylinder and a pressure responsive member slidably mounted therein, an actuator for the device including a casing and a flexible pressure responsive member mounted therein for limited movement with respect to the first named member, means including a control valve having a connection with the cylinder and casing for controlling the pressure of fluid therein and for subjecting said members to the same pressures at

all times, and means including an equalizer for connecting said pressure responsive members and device, said equalizer having movement arms of a length substantially inversely proportional to the areas of the pressure responsive members connected thereto.

7. The combination with a device to be actuated, of a fluid motor for actuating the device including a cylinder and a piston slidably mounted therein, a fluid actuator for the device including a casing and a flexible diaphragm mounted therein for limited movement with respect to the piston, means including a control valve having a connection with the cylinder and casing for controlling the pressure of fluid therein and for subjecting the piston and diaphragm to the same pressure at all times, and means for connecting said piston, diaphragm and device including an equalizer, said equalizer being proportioned to substantially balance the forces exerted by fluid pressure on the areas of the piston and diaphragm.

8. The combination with a device to be actuated, of a fluid motor for actuating the device including a cylinder and a piston slidably mounted therein, a fluid actuator for the device including a casing and a flexible diaphragm mounted therein having a neutral position and arranged for limited movement in either direction from neutral position with respect to the degree of movement of the piston, means including a control valve having a connection with the cylinder and casing for controlling the pressure of fluid supplied thereto and for subjecting said piston and diaphragm to the same pressure at all times, and means for connecting said piston, diaphragm and device including equalizer mechanism connected thereto, said equalizer mechanism being so proportioned as to substantially balance the forces exerted on the piston and diaphragm by the application of fluid pressure thereto when the diaphragm is in neutral position.

9. The combination with a device to be actuated, of a fluid motor for actuating the device including a cylinder, a piston slidably mounted therein, and a packing carried by the piston and in frictional engagement with the cylinder, means including a valve having a connection with the cylinder for controlling the supply of fluid pressure thereto, means including a lever for connecting said piston and device, and means for insuring limited movement of said device on operation of said valve to supply fluid pressure to said cylinder including a fluid actuator having a casing provided with a substantially frictionless pressure responsive member adapted for limited movement with respect to the movement of said piston, means for connecting said member and lever, and a connection between said casing and valve, said diaphragm being so proportioned with respect to said piston and lever as to insure limited movement of said device in response to the application of fluid pressure to said cylinder and casing regardless of the friction between said packing and cylinder.

10. The combination with a device to be actuated, of a fluid motor for actuating said device including a cylinder having a piston slidably mounted therein, means for connecting said pis-

ton and device, means for controlling the pressure of fluid in the cylinder including a control valve having a connection with the cylinder, and means for insuring limited movement of said device in one direction or the other regardless of the friction between said piston and cylinder on operation of said control valve to increase or decrease the pressure of fluid in the cylinder including a fluid actuator having a casing and a pressure responsive member mounted therein for limited substantially frictionless movement in either direction from a neutral position with respect to the movement of said piston, a connection between the cylinder and casing for subjecting the pressure responsive member to the pressure in the cylinder, and an operating connection between the pressure responsive member and connecting means, said operating connection and connecting means being so proportioned with respect to the piston and pressure responsive member that the force exerted by the latter to move the device differs from that exerted by the piston to move the device by substantially the friction force between the piston and cylinder when the piston and pressure responsive member are subjected to the same degree of fluid pressure.

11. The combination with a device to be actuated, of a fluid motor for actuating the device including a cylinder and a piston slidably mounted therein, a fluid actuator including a casing having a flexible pressure responsive member mounted for limited movement with respect to the piston, means including a control valve having a connection with the casing and cylinder for controlling the pressure of fluid supplied thereto and for subjecting the piston and member to the same pressure at all times, and means for connecting said piston, pressure responsive member and device for operating the latter, said connecting means being so proportioned with respect to the area of the piston and pressure responsive member that the force transmitted from the pressure responsive member to the device to move the latter differs from that transmitted from the piston to move the device by substantially the friction force between the piston and cylinder when the piston and pressure responsive member are subjected to the same degree of fluid pressure.

12. Control mechanism for a device to be actuated, said mechanism including a cylinder having a piston slidably mounted therein, a fluid actuator having a casing and a flexible substantially frictionless pressure responsive member mounted therein for relatively limited movement with respect to the movement of said piston, means including a control valve having connections with the cylinder and casing for controlling the degree of fluid pressure supplied thereto and for subjecting the piston and member to the same pressures at all times, and means for connecting said piston, pressure responsive member and device including an equalizer mechanism connected thereto, said equalizer mechanism being so proportioned as to substantially balance the forces exerted on the piston and pressure responsive member by the application of fluid pressure thereto when said member is in neutral position.

WILFRED A. EATON.
